UNITED STATES PATENT OFFICE.

KATE L. BARTHOLOMEW, OF PORTLAND, OREGON.

DESIGN FOR A CAP.

58,302.

Specification for Design.

Patented July 12, 1921.

Application filed September 4, 1919. Serial No. 321,723. Term of patent 3½ years.

To all whom it may concern:

Be it known that I, KATE L. BARTHOLOMEW, a citizen of the United States, residing at Portland, in the county of Multnomah and State of Oregon, have invented a new, original, and ornamental Design for Caps, of which the following is a specification, reference being had to the accompanying drawing, forming part thereof.

In said drawing, Figure 1 shows a top plan view of my design for a cap. Fig. 2, a side elevation of my design for a cap.

The essential feature of my design consists of a plurality of radially disposed segment disks each of the latter having a different color, and the center from which such disks radiate being covered by a plurality of circular disks of different colors.

I claim:

The ornamental design for a cap, as shown.

KATE L. BARTHOLOMEW.
